FOUNTAIN COMB

Charles M. Hickey, New York, N. Y.

Application July 15, 1939, Serial No. 284,743

7 Claims. (Cl. 132—13)

This invention relates to fountain combs and has particular reference to a comb of this character provided with improved means for forcibly feeding a liquid to the teeth thereof.

5 The invention comprehends a fountain comb which is so constructed and arranged as to provide a storage chamber for holding a supply of liquid, a discharge chamber provided with discharge ports through which the liquid is discharged to the teeth, and a pump cylinder communicating with said chambers respectively with a piston mounted for reciprocatory movement within said cylinder and normally urged in one direction and manually moved in the opposite 10 direction for pumping the liquid from said storage chamber and forcing the same into the discharge chamber and through the discharge ports.

The invention more specifically comprehends 20 in a comb of the indicated character, a pump including a pump cylinder having inlet and outlet openings communicating respectively with said supply and discharge chambers and provided with a check valve normally closing the inlet 25 opening and a piston provided with a liquid passageway therethrough and having a check valve for closing said passageway, said piston being adapted upon reciprocation in said cylinder to draw the liquid from said supply chamber 30 through said pump inlet and to force the same through the piston passageway into the discharge chamber.

The invention further embodies a piston having heads at the opposite ends thereof and manipulating means intermediate said heads protruding through an elongated guide slot in said comb for manually actuating said piston.

The invention further includes an air inlet valve normally closed to prevent escape of the liquid in said supply chamber and adapted to be moved to open position for admitting air to the supply chamber by suction created by the pumping of the liquid from said supply chamber.

With the foregoing and other objects in view, 45 reference is now made to the following specification and the accompanying drawing in which there is illustrated the preferred embodiment of the invention.

In the drawing:

50 Fig. 1 is a longitudinal vertical sectional view of a fountain comb constructed in accordance with the invention.

Fig. 2 is an enlarged fragmentary horizontal sectional view taken approximately on the line 55 2—2 of Fig. 1.

Fig. 3 is an enlarged transverse sectional view taken approximately on the line 3—3 of Fig. 1.

Fig. 4 is an enlarged fragmentary vertical sectional view through the comb and air inlet valve.

Referring to the drawing by characters of reference, the comb includes an elongated hollow body 10 provided with a row of teeth 11 extending from one end of the body to the mid portion 12 thereof which is of a reduced size and which, together with the forward end portion 13, is of 10 oval shape in cross sectional configuration so as to serve as a handle.

The body 10 is also provided with a transverse partition 14 which extends from the rear wall of the body to the forward end of the mid portion 12 thereof so as to subdivide the interior of the body into a liquid supply chamber 15 and a liquid discharge chamber 16 and which forms with the bottom wall of the mid portion 12 a cylindrical bore 17 in alignment with the discharge chamber 16 and located between the same and the supply chamber 15. The discharge chamber 16 extends substantially coextensive with the row of teeth 11 and is provided with ports 18 which open through the bottom wall 25 thereof between adjacent pairs of comb teeth.

In order to provide means for feeding the liquid from the supply chamber 15 to the discharge chamber 16 and forcing the same through the ports 18 onto the teeth, a longitudinally reciprocating pump is arranged within the cylindrical bore 17. The said pump includes a pump cylinder 19 which snugly fits the bore 17 and is secured in position therein by a set screw 20. The cylinder 19 has its outlet end in communication with the discharge chamber 16 and its inlet end protruding into the supply chamber 15. Secured within the inlet end is a valve casing 21 having an axial bore 22 provided with a reduced inlet 23 which forms the pump inlet and provides a valve seat 24 for a ball valve element 25. The inlet 23 is normally closed by a coiled expansion spring 26 positioned in the inner end of the bore 22 between the ball valve element 25 and a pin 27 which extends through the walls 40 of the cylinder 19 and secures the valve casing 21 within the said cylinder.

Mounted within the cylinder 19 for longitudinal reciprocation movement therein is a piston 28 which includes a medial portion 29 having a longitudinally extending axial bore 30 provided with interiorly threaded enlarged openings 31 and 32 which are threadededly engaged by exteriorly threaded headed studs 33 and 34. The said studs respectively secure between the heads 55

thereof and the ends of the medial portion 29 packing heads 35 and 36 to thereby provide a pump head at each end thereof. The studs 33 and 34 have bores therethrough which align 5 with the bore 30 and form therewith a liquid passageway through the pump piston.

The enlarged opening 32 at its juncture with the bore 30 forms a valve seat 37 and is provided with a ball valve element 38 adapted to seat on the valve seat 37 for closing the passageway through the piston. The piston 28 is tensioned 10 by a coiled expansion spring 39 positioned within the cylinder 19 between the outlet end thereof and the packing head 36 for normally urging the piston towards the inlet end of the cylinder. The medial portion 29 of the piston 28 is provided with a pair of outwardly projecting manipulating studs 40 which protrude through aligned longitudinally extending slots 41 in the cylinder 19 15 and side walls of the body 10, the heads 42 of which are adapted to be engaged by the fingers for effecting reciprocation of the piston 28 within the cylinder 19. The inlet end of the pump cylinder 19 has fitted thereover a tubing 44 which 20 extends downwardly to dispose its inlet end adjacent the bottom of the liquid chamber 15 so as to dispense and drain the entire contents of 25 the chamber.

The forward end of the handle portion 13 of 30 the body 10 is provided with a threaded filling opening 45 which is closed by a screw plug 46. The opposite end of the body 10 is provided with a bore 47 closed by a screw plug 48 and has an air inlet opening 49 located between a pair of adjacent 35 comb teeth with a port 50 opening into the supply chamber 15 for admitting air into said chamber as the liquid is pumped therefrom. An inwardly opening, outwardly closing check valve is provided which includes a casing 51 fitted into 40 the bore 47 and retained in place therein by the plug 48. The casing is provided with a partition having a port 52 defining a valve seat with which a ball valve 53 is normally engaged by means of a coiled expansion spring 54. The casing is also provided with ports 55 and 56 which align with the inlet opening 49 and the inlet port 50.

In operation the supply chamber 15 is charged 50 with a quantity of a liquid by introducing the same through the charging opening 45 and replacing the plug 46 to seal the said opening. The liquid is then fed to the comb teeth by actuating the pump through the medium of the manipulator heads 42 to reciprocate the piston 28 longitudinally of the pump cylinder 19. As the piston is moved to the left, the valve element 25 is unseated so as to draw the liquid through the tube 44 and the inlet 23 into the pump cylinder, during 55 which movement of the piston the check valve 38 is seated on its seat 37 to close the passageway 30 through the piston 28. The quantity of the liquid drawn into the cylinder between the piston and the check valve 25 is then forced through the passageway 30 by movement of the piston to the right which movement opens the valve 38 and closes the valve 25. The next succeeding movement of the piston 28 to the left forces the liquid from the cylinder into the discharge chamber 16 coincident with the drawing 60 in of an additional quantity of liquid through the inlet 23. Repeated actuation of the piston 28 in like manner will supply the required quantity of the liquid through the ports 18 onto the comb teeth.

75 What is claimed is:

1. In a fountain comb, a hollow body, a row of teeth projecting outwardly along one portion thereof, the interior of said body forming a liquid supply chamber and a liquid discharge chamber, the outer wall of said discharge chamber having 5 ports opening between the teeth of said row, a pump cylinder having an outlet communicating with said discharge chamber and an inlet communicating with said supply chamber, a piston mounted for longitudinal reciprocatory movement within said pump cylinder and having a passageway therethrough, a valve normally closing said inlet and adapted to be opened by movement of the piston in one direction, and a valve adapted to open said passageway by movement 10 of the piston in the opposite direction.

2. In a fountain comb, a hollow body, a row of teeth projecting outwardly along one portion thereof, the interior of said body forming a liquid supply chamber and a liquid discharge chamber, 20 the outer wall of said discharge chamber having ports opening between the teeth of said row, a pump cylinder having an outlet communicating with said discharge chamber and a valved inlet communicating with said supply chamber, a piston mounted for longitudinal reciprocatory movement in said cylinder, said piston having heads at the opposite ends thereof and a valved longitudinal passageway therethrough, said cylinder having a longitudinally extending guide slot, and 25 manipulating means intermediate the heads of said piston protruding through said guide slot for manually actuating said piston.

3. In a fountain comb, a hollow body, a row of teeth projecting outwardly along one portion 35 thereof, the interior of said body forming a liquid supply chamber and a liquid discharge chamber, the outer wall of said discharge chamber having ports opening between the teeth of said row, a pump cylinder having an outlet 40 communicating with said discharge chamber and an inlet communicating with said supply chamber, a valve normally closing said inlet, a piston having a passageway therethrough, and a valve adapted to close the same, said piston being 45 mounted in said cylinder for longitudinal reciprocatory movement for drawing the liquid from said supply chamber through said inlet and pump cylinder valve and for forcing the same 50 through said piston and piston valve and into said liquid discharge chamber.

4. In a fountain comb, a hollow body, a row of teeth projecting outwardly along one portion thereof, the interior of said body forming a liquid supply chamber and a liquid discharge chamber, 55 the outer wall of said discharge chamber having ports opening between the teeth of said row, a pump cylinder having an outlet communicating with said discharge chamber and an inlet 60 communicating with said supply chamber, a piston mounted for longitudinal reciprocatory movement within said pump cylinder and having a passageway therethrough, a valve normally closing said inlet and adapted to be opened by movement of the piston in one direction, a valve 65 adapted to open said passageway by movement of the piston in the opposite direction, and spring means acting upon said piston for urging the same in a direction so as to open said last mentioned valve and to automatically discharge the 70 liquid from the pump cylinder into the discharge chamber and through the ports onto the teeth.

5. A fountain comb including a hollow body having a row of teeth projecting outwardly therefrom, said body being subdivided into a liquid 75

- storage chamber and a liquid discharge chamber extending longitudinally of said row of teeth and having longitudinally spaced discharge ports opening between the teeth of said row, a pump 5 including a pump cylinder communicating respectively at its opposite ends with said chambers, a reciprocatory piston in said cylinder adapted to feed the liquid from said supply chamber to said discharge chamber and through said 10 discharge ports onto the teeth, and manipulating means connected with said piston and protruding through said cylinder and exposed on opposite sides of the body for actuating said pump cylinder.
- 15 6. In a fountain comb, a hollow body, a row of teeth projecting outwardly along one portion thereof, a wall subdividing the hollow body into a liquid supply chamber and a liquid discharge chamber with a pump receiving bore disposed in alignment with said discharge chamber, the wall 10 of said discharge chamber having ports opening between the teeth of said row, a pump including a cylinder fitted and secured within said bore and having an outlet communicating with said 15 discharge chamber and an inlet communicating with said supply chamber, a piston mounted for longitudinal reciprocatory movement within said cylinder and having a passageway therethrough, a valve normally closing said inlet and adapted to be opened by movement of the piston in one direction, a valve adapted to open said passageway by movement of the piston in the opposite direction, and said piston having heads at the 20 opposite ends thereof, and manipulating means intermediate the said heads protruding through slots in said body and cylinder for manually actuating said piston.
7. In a fountain comb, a hollow body, a row of teeth projecting outwardly along one portion thereof, a wall subdividing the hollow body into a liquid supply chamber and a liquid discharge chamber with a pump receiving bore disposed in alignment with said discharge chamber, the wall 5 of said discharge chamber having ports opening between the teeth of said row, a pump including a cylinder fitted and secured within said bore and having an outlet communicating with said discharge chamber and an inlet communicating with said supply chamber, a piston mounted for longitudinal reciprocatory movement within said cylinder and having a passageway therethrough, a valve normally closing said inlet and adapted to be opened by movement of the piston in one direction, a valve adapted to open said passageway by movement of the piston in the opposite direction, and said piston having heads at the 15 opposite ends thereof, and manipulating means intermediate the said heads protruding through slots in said body and cylinder for manually actuating said piston.
- 25 8. In a fountain comb, a hollow body, a row of teeth projecting outwardly along one portion thereof, a wall subdividing the hollow body into a liquid supply chamber and a liquid discharge chamber with a pump receiving bore disposed in alignment with said discharge chamber, the wall 20 of said discharge chamber having ports opening between the teeth of said row, a pump including a cylinder fitted and secured within said bore and having an outlet communicating with said discharge chamber and an inlet communicating with said supply chamber, a piston mounted for longitudinal reciprocatory movement within said cylinder and having a passageway therethrough, a valve normally closing said inlet and adapted to be opened by movement of the piston in one direction, a valve adapted to open said passageway by movement of the piston in the opposite direction, and said piston having heads at the 25 opposite ends thereof, and manipulating means intermediate the said heads protruding through slots in said body and cylinder for manually actuating said piston, and said body having an air inlet valve opening into the supply chamber adapted to be moved to open relation for admitting air to the supply chamber by suction created by the pumping of the liquid from said chamber.
